UNITED STATES PATENT OFFICE.

JAMES A. EARLEY, OF TYRO, KANSAS.

PUMPING JACK.

Application filed October 30, 1922. Serial No. 597,813.

To all whom it may concern:

Be it known that I, JAMES A. EARLEY, a citizen of the United States, residing at Tyro, in the county of Montgomery and State of Kansas, have invented certain new and useful Improvements in Pumping Jacks, of which the following is a specification, reference being had therein to the accompanying drawings.

This invention relates to a pumping jack for use in connection with water or oil wells and it has for its object to provide an improved device of this character constructed in such manner that the polish or pumping rod will not be subjected to any lateral or twisting strain but that upon the contrary the force exerted thereon will always be a straight line movement. This not only results in relieving the pumping rod of undesirable strains which tend to move it out of alinement with the casing but it utilizes the motion ordinarily lost by the ordinary pivoted jack.

It is a further object of the invention to provide a jack of the character described of a nature particularly adapted for use in connection with a source of power disposed at a more or less distant point.

Further objects and advantages of the invention will be set forth in the detailed description which follows.

In the accompanying drawings:

Fig. 1 is a side elevation of a pumping jack constructed in accordance with the invention;

Fig. 2 is a plan view thereof;

Fig. 3 is a horizontal sectional view upon line 3—3 of Fig. 1;

Figs. 4 and 5 are detail sectional views illustrating thrust bearings hereinafter described; and

Fig. 6 is a vertical sectional view upon line 6—6 of Fig. 1.

Like numerals designate corresponding parts throughout the several figures of the drawings.

In the drawings 5 and 6 designate longitudinally extending sills, 7 a cross bar, 8 the casing head and 9 the polish or pump rod. These parts are all of the usual and well known construction and need no further description. Power is imparted to the pumping jack through a rod or cable 10 which is connected to a yoke 11 and which yoke, in turn, engages in any desired one of the notches 12 of a clevis 13. This clevis is

carried by a pull rod post 14 and this pull rod post is suitably braced by a brace bolt 15 and brace rods 16, 17 and 18 from a main beam 19 which comprises spaced channel 60 irons 19^a and 19^b. Mounted between these spaced channel irons which constitute the beam 19 is a rear bearing block 20 an intermediate bearing block 21 and a front bearing 65 block 22. The intermediate bearing block 21 carries an elongated circular rib 23 upon its lower face which bears in a concave recess formed in the upper face of a bearing plate 24. This bearing plate is slidably mounted upon ribs 25 of a lower 70 bearing plate 26, said lower bearing plate being carried by the sills 5 and 6. Adjusting screw 27 passes through an upstanding edge 26' of the lower bearing plate 26 and engage bearing plate 24 to adjust it upon 75 plate 26 and thus to accurately position it with respect to the rib 23. The upper face of the front bearing block 22 has a concave recess formed therein which receives an elongated rib 28 carried by a bearing head 29 80 upon the lower end of a front pitman 30. The upper end of this pitman is provided with a cup-like bearing head 31 which receives a rounded head 32 of a bearing plate 33, the latter being carried by an upper 85 beam 34 consisting of spaced channel irons 34^a and 34^b. The front end of the beam 34 carries a bearing block 35 having concave recesses 36 formed therein which receive trunnion like elements 37 of a collar 38 90 which is carried by pump rod 9. The rear end of the upper beam 34 carries a cup plate 39 which is shaped to receive a rounded rib 40 formed upon an upper bearing plate 41. Rods 42 complementally constituting 95 a yoke pass through extensions of the plate 41 and have nuts 43 upon their upper ends. The lower ends of these rods pass through a lower bearing plate 44 which is cupped to receive a rounded rib 45 formed upon a 100 bearing plate 46, said bearing plate 46 being in turn secured in position between channel irons 47^a and 47^b which constitute an intermediate beam 47. The intermediate beam 47 carries upon its upper face, intermediate 105 its ends, a bearing plate 48 having a recessed portion which engages with a rounded rib 49 formed upon the lower side of a bracket 50, which bracket is secured in position between fixed, vertical channel irons 51, the 110 lower ends of which are supported from the sills 5 and 6. The bracket 50 has an exten-

2

sion 52 projecting forwardly therefrom which supports a vertical guide rod 53. This guide rod is braced by a brace rod 54 from a rear extension 55 of the bracket 50. 5 A guide iron 56 projects from the rear end of the upper beam 34 and its rear end slidably engages the guide rod 53, as indicated at 57, whereby the parts are held in proper alinement with each other throughout the 10 operation of the pump. The rear end of the intermediate beam 47 is provided with a bearing plate 58, the lower end of which carries a rounded rib 59 which has its seating in a cup-like bearing head 60 of a rear pitman 61. The lower end of this pitman is provided with a bearing head 62 having a rounded lower rib 63 which engages in a cup-like upper surface of the bearing plate 20 at the rear end of the main beam 19. 20 Thus when the rod 10 is pulled upon, the pull rod post 14 is rocked toward the left in Fig. 1 and this, in turn, rocks the beam 19 upon its pivot 23 and thrust upwardly upon the pitman 30. This in turn thrusts the upper beam 34 upwardly and during its upward movement this beam 34 is maintained in a substantially horizontal position due to the fact that while the upward thrust of the pitman 30 tends to lift the rear end of beam 34 30 as well as the front end thereof, the rear end cannot rise any faster than it is permitted to do by the yokes constituted by rods 42 which are, in turn, restrained by the movement of beam 47 the front end of which beam can only move upwardly as the rear end of the main beam 19 moves downwardly. 35

In other words the parts are so interconnected that nearly all of the energy is utilized in imparting a direct straight line upward thrust to the pump rod 9, the beam 34 being maintained in a horizontal position throughout its up and down movement. When the pump rod 9 reaches its upward limit of movement and the rod or cable 10 is slackened in the usual way, the weight of the pump rod and pump plunger (not shown) immediately draws the rod downwardly and moves the parts in the opposite direction and it will be observed that the thrust of all of the parts is such as to maintain the several bearing elements in engagement with each other. In other words while these bearing elements merely rest upon each other and are not positively connected, the direction of thrust is such as to maintain them in engagement with each other. However, it will be observed that all of these elements comprise parts of cup-like formation adapted to receive and maintain oil with the result that a pump jack of this nature needs very little attention, is of simple and economical construction and will efficiently do the work required with a minimum of wear upon the parts.

65 It is to be understood that the invention

is not limited to the precise construction set forth but that it includes within its purview whatever changes fairly come within either the terms or the spirit of the appended claims.

Having described my invention what I claim is:

1. In combination a vertically disposed pump rod, a main beam, an intermediate beam and an upper beam, a connection between one end of the upper beam and the pump rod, a connection between the rear end of the upper beam and the intermediate beam, a connection between the rear end of the intermediate beam and the rear end of the main beam and a connection between the front end of the main beam and the intermediate part of the upper beam.

2. In combination a main beam, means for supporting said main beam to rock, a vertically disposed pump rod, an upper beam and an intermediate beam, a rocking bearing between the pump rod and one end of the upper beam, a yoke connecting the rear end of the upper beam with the front end of the intermediate beam and having rocking engagement with both of them, a pitman connecting the front end of the main beam with an intermediate part of the upper beam and having rocking engagement with both of them, a pitman connecting the rear end of the intermediate beam and the rear end of the lower beam and having rocking engagement with both of them, and means for imparting rocking movement to the main beam.

3. A device of the character described comprising a supporting base, a bearing block thereon, a main beam mounted to rock upon said bearing block, upstanding fixed members carried by the base, an intermediate beam, a rocking bearing between the intermediate beam and said upstanding members, an upstanding guide rod carried by said fixed members, an upper beam, a guide iron carried by the upper beam and engaging said guide rod, a vertically disposed pump rod, a rocking bearing between the front portion and the upper beam and said pump rod, a pitman extending between the intermediate portion of the upper beam and the front end of the main beam and having rocking engagement with both of them, a connecting link extending between the rear end of the upper beam and the front end of the intermediate beam and having rocking engagement with each of them, a pitman extending between the rear end of the intermediate beam and the rear end of the main beam and having rocking engagement with each of them, and a pull rod post carried by the main beam and suitably braced therefrom.

In testimony whereof I hereunto affix my signature.

JAMES A. EARLEY.
